APPARATUS FOR MIXING CONCRETE AND
THE LIKECharles F. Ball, Wauwatosa, Wis., assignor to
Chain Belt Company, Milwaukee, Wis., a cor-
poration of Wisconsin

Application September 9, 1936, Serial No. 100,008

8 Claims. (Cl. 259—175)

This invention relates to apparatus for mixing concrete and the like, and has for one of its objects to provide an improved construction of multiple compartment mixing receptacle for such apparatus.

A further object of the invention is to provide an improved closure mechanism for controlling the drum openings of concrete mixing apparatus.

A further object of the invention is to provide improved mechanism for actuating said closure.

A still further object of the invention is to provide power actuated mechanism for operating the closure, which includes yieldable means arranged to prevent damage to the parts in the event of a piece of large aggregate or other unyielding material being caught between the closure and its seat in its closing movements.

A still further object of the invention is to provide an improved connection between the closure carrying shaft and the actuating arm therefor, said connection serving to translate rocking movements of the arm into axial movements of the shaft while permitting free rotation of the shaft upon its axis.

With the above and other objects in view which will appear more fully below, the invention consists in the novel details of construction, and combinations of parts, more fully hereinafter described and particularly pointed out in the appended claims.

Referring more particularly to the accompanying drawings forming a part of this specification in which like reference characters designate like parts in all the views:

Figure 1 is a central longitudinal sectional elevational view of one form of concrete mixing or agitating receptacle, closure, and operating mechanism therefor, constructed in accordance with the present invention;

Fig. 2 is an enlarged longitudinal sectional view, partly in elevation, of a portion of the closure carrying shaft, its support, and its connection with the closure, the extreme right hand portion of the view being taken approximately on the planes indicated by the line 2—2 of Fig. 4;

Fig. 3 is a transverse sectional elevational view of the shaft and its splined support, taken approximately on the plane indicated by the line 3—3 in Fig. 2;

Fig. 4 is a transverse sectional elevational view, taken approximately on the plane indicated by the line 4—4 in Fig. 2;

Fig. 5 is an end elevational view of the improved connection between the closure carrying shaft and its actuating rock arm;

Fig. 6 is a central vertical sectional view, partly in elevation, of said connection, taken approximately on the plane indicated by the line 6—6 in Fig. 5;

Fig. 7 is a longitudinal sectional elevational view of one form of yielding means for preventing damage to the parts as above set forth; and

Fig. 8 is a fragmentary sectional view of a slightly modified form of connection between the closure and its supporting shaft.

Referring more particularly to Fig. 1, the multiple compartment drum or receptacle comprises a tubular shell 10 preferably although not necessarily circular in cross section, the open ends of which are closed by the heads 11 and 12, riveted, welded, or otherwise rigidly secured therein. The head 11 is provided with the charging opening 13 which may have associated therewith the charging chute 14 for conducting the raw materials into the drum, and the head 12 is provided with the discharge opening 15 which may have associated with it any suitable and well known form of discharge chute or mechanism not shown, since it in itself constitutes no part of the present invention. This discharge chute may be either manually operable or automatically operable, by suitable power mechanism, as is well known in the art.

Intermediate the heads 11 and 12 is the transverse partition 16 having a central transfer opening 17 preferably surrounded by an angle member 18 which strengthens the partition at this point and serves as a seat for the closure member 19 which controls the transfer of the partially mixed materials from the preliminary mixing compartment 20 into the final mixing compartment 21 into which the transverse partition divides the receptacle. The closure member 19 is carried by an axially extending hollow shaft 22 being joined thereto at the inner end of the latter by a connection 23 which will be described more in detail hereinafter.

The shaft 22 extends longitudinally through the compartment 20 with an extension 19 therefrom projecting through the charging opening 13 and charging hopper 14, as will be readily understood from Fig. 1, and having its exterior end connected by a ball and socket joint 24, to be more fully hereinafter described, with one end of a rock arm or lever 25, the other end of which is rigidly connected to a rock shaft 26 suitably journaled in the framework of the apparatus, not shown. The said rock shaft 26 also rigidly carries an arm or lever 27 the free end of which is pivotally connected as at 28 to one end of a

link 28, the other end of which is pivotally connected as at 30 to one arm 31 of a bell crank lever pivoted as at 32 upon the framework. The other arm 33 of said bell crank lever is pivotally connected as by the pin 34 to one end of a link or pitman 35 which preferably embodies a yieldable overload release mechanism to be more fully hereinafter described, and the other end of which is pivotally connected as at 36 to the 5 rotating or oscillating arm 37 of the power discharge mechanism 38 which is or may be substantially of the construction set forth and claimed in the prior U. S. Patent to Samuel Shafer, Jr., granted May 9, 1922, No. 1,415,411.

10 15 The drum or receptacle 18 is further provided with the circumferentially extending tracks 40 receivable upon suitable supporting rollers, not shown, journaled on the framework of the machine and the said drum may also be provided 20 with the sprocket or equivalent power transmitting element 41 by means of which the drum may be rotated in the usual and well known manner.

The preliminary mixing chamber 20 is provided with a coniform shield and deflecting member 44, as well as with a plurality of mixing blades 45 only two of which are here shown, and with a plurality of transfer blades or troughs 46, which extend along the inner surface of the coniform deflecting member 44 which extends from the outer shell 18 to the transfer opening 17, as will be readily apparent from Fig. 1. The coniform member 44 not only tends to guide the mixture to the transfer opening 17, but also serves 30 to brace and reinforce the transverse partition 48, as well as to prevent concrete from collecting in the corner joint between the said partition and the outer shell 18, where it would otherwise harden and build up to such an extent as to 35 have to be frequently chipped out by hand. The number of mixing blades 45 and the transfer blades or troughs 46 may vary, one typical example thereof being six mixing blades such as 45, and three transfer troughs 46, which latter 40 preferably form continuations of an alternate three of the mixing blades as shown in the upper portion of the preliminary mixing chamber. In like manner the final mixing chamber 21 is provided with a plurality of mixing blades 47 and a 45 plurality of discharge buckets 48, and the numbers of these blades and buckets will likewise vary, one typical example thereof being six mixing blades 47, and 12 discharge buckets 48.

As will be clear from Fig. 1, the outer end of 50 the hollow shaft 22 is supported by the ball and socket connection 24 and rock arm 25, and the inner end of the said shaft is supported by a slide bearing which, as here shown, comprises a plate 50, see also Figs. 2 and 3, substantially vertically disposed within the preliminary mixing chamber 20 adjacent the transfer opening 17 and welded or otherwise rigidly secured to the transfer blades or troughs 46. The said plate 50 carries a plurality of fingers or projections 51, the 55 inner ends 52 of which are slidably receivable in the longitudinal extending channel members 53, which are welded or otherwise rigidly secured upon the exterior surface of the hollow shaft 22. The said shaft is thus splined to the support 50 being freely axially slidable therethrough but 60 positively rotatable therewith, as will be readily understood.

As best shown in Figs. 2 and 4, the connection 65 between the transfer closure 19 and the hollow shaft 22 comprises a ball member 60 mounted

upon the squared end 61 of the stud 62 which is received in and rigidly secured to the extreme end of the hollow shaft 22. The said ball member 60 is enclosed by a socket 63 comprising two members 64 and 65 which are separable and have the closure plate 19 clamped between them. The ball member 60 is provided with a plurality of radially extending lugs 66 which are receivable in recesses 67 formed in the socket members 64 and 65 which recesses are of such dimensions relative to those of the lugs that limited oscillatory movements of the socket members and closure 10 15 plate 19 are permitted in the direction of the axis of the shaft 22 but relative circumferential movement between the ball member and the socket and plate is prevented. It results from this construction that although rotary motion of the shaft is positively transmitted through the lugs and recesses to the socket and closure member 19, the latter at the same time may oscillate axially to accommodate itself to the seating ring 18 and thus provide a reasonably tight closure 20 between the said ring and plate, as will be readily understood.

In order to prevent entry of constituents of the concrete mixture into the connection 23 there is preferably provided a rubber or other yielding sleeve 68 one end of which is clamped as by a ring 69 to the socket member 64, while the other end thereof is clamped as by a ring 70 to a flange 71 rigidly secured to the stud 62, all as will be clear from Fig. 2.

The ball and socket connection 24 between the outer end of the shaft 22 and rock arm 25 is shown in detail in Figs. 5 and 6, and comprises a housing 75 formed with a partly spherical socket 76 which receives the ball member 77. The said ball member 77 is axially bored for the reception of an anti-friction bearing 78 which serves as a journal for the extreme outer end of the stud shaft 79 which is rigidly secured by welding or otherwise to the hollow shaft 22. One end of the bore in the ball 77 is preferably closed by the threaded cap member 80, while the other end of said bore is provided with a suitable seal 81 which seal and cap prevent entry of the concrete constituents into the bearing. The housing 75 is provided with a pin or stud 82 one end 83 of which projects into an elongated recess 84 formed in the ball member 77 and which serves to prevent rotation of the ball relative to the housing while at the same time permitting of oscillating movements thereof in the plane of the shaft axis.

The stud 62, stud shaft 79 and cap member 80, 55 are preferably provided with the axial lubrication passages 85, 86, and 87, respectively, whereby suitable lubricant may be introduced to the parts.

While the yielding overload mechanism incorporated into the pitman 35 may take various forms, that shown in detail in Fig. 7 has been found quite effective in actual use. Referring more particularly to the said figure, the mechanism may comprise a stud 90 having an eye 91 for the reception of the pin 34 and which stud is threaded as at 92 into one end of a tubular housing member 93, the other end of which housing is threaded as at 94 into the complementary end of the tubular housing member 95. A rod or shaft 96 having an eye 97 for the reception of the pin 36 slidably enters 70 the housing member 95 through a bearing 98 and extends therethrough as well as into the housing member 93, being provided at its other end with a head 99 which serves as a seat for one end of a coiled compression spring 100, the 75

other end of which is seated against a sleeve or bushing 101 which has a ball or anti-friction bearing 102 interposed between it and the shoulder 103 of the housing member 95. It will thus be apparent that if during the closing movements of the closure 19 a stone or other unyielding piece of material should be caught between the closure and the seating ring 18, thereby resisting further closure of the member 19, no damage to the parts will result since the motion being transmitted to the shaft 22 and closure 19 through the rock arm 25, arm 27, link 29, bell crank lever 31 and 33 and pitman 35 from the power actuating arm 37 of the power discharge device 38 will merely compress the spring 100 while permitting those elements beyond the rod 96 to stop their movement.

As is readily understood by those skilled in the art, in the use of these multiple compartment drums or receptacles, the raw materials which go to make up a batch of concrete are introduced into the preliminary mixing chamber such as 20 through the charging chute 14 and are there mixed for a portion only of the predetermined mixing period, after which they are transferred into the final mixing chamber 21 and the mixing of that batch completed, while a fresh batch is being introduced into and preliminarily mixed in the chamber 20. Of course, during the preliminary mixing in chamber 20 of the initial batch the closure 19 is moved to the left, as viewed in Figure 1, to seat against the ring 18, while, when the predetermined portion of the mixing cycle has been completed, the power mechanism 38 will automatically move the closure to the position shown in Fig. 1, so that the partially mixed batch may be transferred through the transfer opening 17 into the final mixing chamber 21 whereupon the mechanism 38 will again close the transfer opening and the preliminary mixing of the second batch as well as the final mixing of the first batch will be simultaneously completed with the closure 19 closed. At the completion of the mixing in chamber 21 the usual discharge chute is manipulated either manually or automatically to discharge the completely mixed batch from the receptacle whereupon the cycle is repeated.

In the somewhat modified form of connection between the closure and shaft illustrated in Figure 8, the end of the shaft is provided with a stud 105 having an enlarged head 106, which is positioned between the opposite rubber or other yielding blocks or members 107 and 108. The said blocks and head are enclosed by a housing 109, secured as by bolts 110 to the central part of the closure 19, and as will be readily understood, the construction provides for universal movement of the closure relative to the shaft, as in the preferred construction.

While one form of the invention has been illustrated and described it is obvious that those skilled in the art may vary the details of construction as well as the precise arrangement of parts without departing from the spirit of the invention and therefore it is not wished to be limited to the above disclosure except as may be required by the claims.

What is claimed is:—

1. In apparatus for mixing or agitating concrete and the like, a receptacle comprising a tubular shell having end walls provided respectively with a charging and a discharging opening; a partition wall intermediate said end walls dividing the receptacle into preliminary and

final agitating compartments, said partition wall extending substantially perpendicular to the perimetral walls of said shell, and having a transfer opening affording communication between said compartments; a coniform member 5 in said preliminary agitating compartment, secured to the perimetral walls of said shell and to said partition adjacent said transfer opening, and arranged to brace said partition wall as well as to deflect material toward said opening and prevent its collecting in the joint between said partition and shell; mixing blades in said compartments; transfer blades in said preliminary agitating compartment disposed substantially parallel to said coniform deflecting member and extending to said transfer opening; and means for controlling the passage of material through said transfer opening.

2. In apparatus for mixing or agitating concrete and the like, a receptacle comprising a tubular shell having end walls provided respectively with a charging and a discharging opening; a partition wall intermediate said end walls dividing the receptacle into preliminary and final agitating compartments, and having a transfer 20 opening affording communication between said compartments; a bracing member secured to said partition and shell, arranged to also prevent building up of material deposits in the corner 25 joint between the partition and shell; material-transfer blades in said preliminary agitating compartment arranged to direct material to and through said transfer opening; a support carried by said blades; a longitudinally movable shaft mounted in said support; and a closure 30 member carried by said shaft in cooperative relation to said transfer opening, arranged to control the passage of material therethrough.

3. In apparatus for mixing or agitating concrete and the like, a receptacle comprising a tubular rotatable shell having end walls provided respectively with a charging and a discharging opening; a partition wall intermediate said end walls dividing the receptacle into separate agitating compartments, and having a central 40 transfer opening affording communication between said compartments; a coniform member secured around the perimeter of the transfer opening in said partition wall and extending therefrom to said shell, arranged to brace said 50 partition wall and deflect material in one of said compartments toward said opening; transfer blades in one of said compartments arranged to direct material to and through said transfer opening; a support secured to said blades and 55 rotatable therewith; a shaft extending axially through said charging and transfer openings, and splined in said support for axial movement relative thereto and rotary movement therewith; a closure member mounted on said shaft for 60 limited oscillatory movements, arranged to control the passage of material through said transfer opening; and power actuated connections exterior of the receptacle arranged to automatically move said shaft in its support to open and 65 close said closure.

4. In apparatus for mixing or agitating concrete and the like, a rotatable receptacle comprising a tubular shell having transverse walls defining a mixing compartment, said walls having aligned openings for ingress and egress of the material; a support adjacent said egress opening, rotatable with said shell; an axially movable shaft extending through said openings and splined adjacent one end in said support; a 75

closure member carried by said shaft for movement to and from said egress opening to control the passage of material therethrough; a rock arm mounted exteriorly of the receptacle adjacent said ingress opening, arranged to constitute the sole support for the outer end of said shaft; a connection between said outer end of the shaft and said rock arm, arranged to translate swinging movements of said arm into axial movements of said shaft while providing for rotation of the shaft about its axis; and means for moving said rock arm.

5. In apparatus for mixing or agitating concrete and the like, a rotatable receptacle comprising a tubular shell having transverse walls defining a mixing compartment, said walls having aligned openings for ingress and egress of the material; a support adjacent said egress opening, rotatable with said shell; a shaft extending through said openings, and splined adjacent one end in said support; a closure member carried by said shaft for movement to and from said egress opening to control the passage of material therethrough; a rock arm mounted exteriorly of the receptacle adjacent said ingress opening; a connection between the other end of said shaft and said rock arm, supporting said last named shaft end on said arm and arranged to translate swinging movements of said arm into axial movements of said shaft while providing for rotation of the shaft upon its axis; power means for moving said rock arm; and yieldable means in the closure operating system for preventing damage to the parts should a piece of unyielding material be caught in the closing movements of said closure.

6. In closure mechanism for an opening of a concrete mixing receptacle, a shaft mounted for axial movements relative to the receptacle and rotary movement therewith; a closure carried by said shaft for movement thereby to and from said opening; and a ball and socket joint between said closure and shaft providing for limited axial oscillation of the closure relative to the shaft, there being lugs formed on one member of said joint, receivable in recesses formed in the other member thereof, for preventing circumferential movement of the closure relative to the shaft.

7. In closure mechanism for an opening of a concrete mixing receptacle, a shaft mounted for axial movements and provided with a head; a closure member having a housing enclosing said head; and resilient members interposed between said head and said closure and housing arranged to provide for axial oscillation of the closure relative to the shaft.

8. In closure mechanism for an opening of a concrete mixing receptacle, a shaft mounted for axial movements; a closure carried thereby for movements to and from said opening; a rock arm for imparting movements to said shaft; and a connection between said rock arm and shaft including a socket member, a ball member mounted therein for oscillatory movements, and a bearing within said ball member journaling said shaft for rotation about its axis relative to said ball and socket members.

CHARLES F. BALL. 35
